C. L. WEIL,
PROCESS FOR THE MANUFACTURE OF SALT,
APPLICATION FILED MAY 13, 1911.

1,141,999.

Patented June 8, 1915.

UNITED STATES PATENT OFFICE.

CHARLES L. WEIL, OF ST. CLAIR, MICHIGAN, ASSIGNOR TO DIAMOND CRYSTAL SALT COMPANY, OF ST. CLAIR, MICHIGAN, A CORPORATION OF MICHIGAN.

PROCESS FOR THE MANUFACTURE OF SALT.

1,141,999.

Specification of Letters Patent.

Patented June 8, 1915.

Application filed May 13, 1911. Serial No. 626,939.

To all whom it may concern:

Be it known that I, CHARLES L. WEIL, a citizen of the United States, and a resident of St. Clair, in the county of St. Clair and State of Michigan, have invented new and useful Improvements in Processes for the Manufacture of Salt, of which the following is a specification.

The invention relates to improvements in the manufacture of salt and consists in certain processes hereinafter fully explained by the employment of which two highly important objects, among others, may be accomplished, to wit: (1) the control of the proportions of the amounts of the various kinds of salt (that is kind with respect to fineness or coarseness of grain) made in a given time under practically normal conditions of operation or, in other words, the control of the grain of the salt produced and the variation of such grain at will, and (2) the acceleration of that step of the process carried on in the evaporating-pan by means other than but capable of cooperating with that employed to enable the control of the character of grain produced.

In the commercial production of salt, in addition to securing economy of operation and purity of product, it is desirable to control the size of the grains. Grains of different sizes are required for different uses and the demand varies accordingly. It is accordingly of great importance to the manufacturer that the process employed be capable of producing at the will of the operator grains of such size as he may require at any particular time, and the invention herein described is designed, among other things, to meet that condition.

It may be premised that in the formation of salt by evaporating saturated brine, the size of the grains of salt is acquired both at the surface of the liquor in the evaporating pans and beneath the surface; that is to say, the particles tend to knit together on the surface and also to build themselves up beneath the surface, so that it is desirable to control both these operations. The size of the grains is accordingly affected by conditions at the surface and beneath the surface. This is particularly true where evaporation is not effected by direct application of heat to the brine in the evaporating pan but by heating the brine under pressure elsewhere, allowing self-evaporation and trans-

ferring the liquid, in which graining has begun, to the evaporating pan for completion of the graining operation. Where the liquid is directly heated during the formation of grain the phenomena are more complicated. At the surface the principal conditions affecting the size of the grains are the period during which they remain on the surface and the rate of evaporation. The principal condition beneath the surface affecting the size of the grain is the period during which the grain remains in the liquor before being taken therefrom.

The process herein described deals with each and all of these conditions and provides for the regulation of the size of the grains at the will of the operator to a nicety. But it will be understood that some of the steps in the process herein described may be omitted without completely losing control of the size of the grains and without departing from the spirit of the invention or scope of the claims.

Many of the steps in the process improve the manufacture of salt in other respects as well as in that hereinbefore indicated. For example, the period during which the grains remain at the surface is regulated preferably by air under pressure. This not only possesses many mechanical advantages but also eliminates the serious danger of producing impurity in the product, which would be involved if beaters or flippers were used, as well as avoiding the difficulty of proper working and the waste involved in cleaning which would attend their use. Again, the regulation of the rate of evaporation which the process in its preferred form provides for by the use of air confined in a hood over the evaporating pans not only gives better control of the size of the grains but also results in greater purity by the elimination of dust, cinders, etc., from over the pans (which in actual practice often results in an inferior product) and also makes the rooms containing the evaporating pans comfortable (instead of almost unbearable as at times at present) for those working therein and secures a regular output regardless of weather conditions instead of making the output dependent upon the atmospheric conditions as at present.

In these and other ways the process as a whole produces salt of great purity and gives the manufacturer greater control over

its production, and several of the steps in the process in themselves represent important improvements in the art.

In order that the process may be clearly understood, there is shown in the accompanying drawing an illustrative apparatus which may be conveniently used in practising the process. The drawing is illustrative only and admits of variation in nearly all its parts, and therein:

Figure 1 is a side elevation, mainly in diagram and partly broken away and partly in section, of suitable apparatus for the practice of my invention, and Fig. 2 is a vertical section, on a larger scale, of a portion of the evaporating or circulating-pan for the brine, with a portion of the air-pipes by means of which air is caused to effect a special and variable agitation of the surface 20 of the brine in said pan.

In the drawings I illustrate a system of apparatus for making salt from brine, whose parts, with the exception of certain features involving my invention, generally speaking, are of structures well-known in the art and do not require elaborate explanation.

Referring to the drawing, 10 designates a circulating and pressure pump while 11 is a live-steam or pressure heater through which 30 the brine passes, becoming heated to a comparatively high temperature; a temperature above its normal boiling point under atmospheric pressure. This is for the double purpose of causing gypsum to become insoluble and separate and of heating the brine to such a point that upon subsequent release of pressure and consequent self-evaporation it will become concentrated enough to deposit salt crystals. Element 12 is a filter 35 through which the brine passes to remove the separated gypsum. Element 13 is a self-evaporator to which the brine passes from the filter 12 and which is open to the atmosphere, by reason whereof the pressure 40 under which the brine had been previously held or maintained through the resistance of the system is released with evolution of vapor and the temperature of the brine is brought down to 226° Fahrenheit, which is 45 50 the temperature of boiling brine at atmospheric pressure. Element 14 is an evaporator or circulating-pan which receives the concentrated brine from the evaporator 13, and 15 a suction heater which receives the 55 brine from the pan 14 and is in communication through a pipe 16 with the pump 10. The brine in proper quantities is fed to the heater 15 through a supply pipe 17. Evaporation of the brine takes place in the 60 pan 14 with formation of salt grain and building up of those grains already formed, and the brine cools down, finally reaching the temperature of about 200° Fahrenheit, and hence the salt is formed in the pan. 65 The pan is equipped with a rotary rake com-

prising blades 18 carried by radial arms 19 extending from a central spider, this rake being a feature well-known in the art. The rake, when rotated, causes its blades 18 to move the salt forming in the pan to a well 70 20 into which the salt falls and from which it is drawn, together with a certain amount of brine, to the customary centrifugal machine 21 which is employed to partially dry the salt. The brine from the centrifugal 75 machine 21 is saved and passed back to the system. The salt after treatment by the centrifugal machine is sent to salt-driers and then screened according to usual custom. The circulation of the brine through 80 the system is continuous and, as hereinbefore explained, the increment of fresh brine necessary to maintain the volume is supplied through the pipe 17. The heaters 11, 15 are of known character, and each comprises a 85 cylindrical vessel containing small tubes (not shown) through which the brine passes and which vessel exterior to the small tubes is kept filled with steam, live-steam being supplied to the heater 11. Usually the steam supplied to the heater 15 is the exhaust of 90 auxiliaries. The filter 12 is also of a known type and comprises a cylindrical vessel partly filled with small stones which present 95 a large amount of surface for the deposit of gypsum or calcium sulfate carried by the brine.

The new features of the apparatus pertaining to a part of the present invention reside in the hood 22 covering the pan 14 100 and having an outlet 23 for vapor, and a main air pipe 24 supplied with air under pressure from a blower 25 and having at suitable intervals branch pipes or nozzles 26 extending downwardly and inwardly near the outer edges of the pan 14 to near the normal level of the brine in the same and constructed to cause a lateral passage of air over the hot brine. The nozzles 26 are provided with regulating valves 27 and the air leaving them will strike the surface of the brine obliquely and create a marked agitation 105 on the surface of the brine, in the nature of a distinct ripple.

A further feature of novelty connected 115 with my invention and pertaining to the pan 14 resides in the delivery within the chamber formed by the hood 22 of a constant supply of heated air. This air may be heated by any of the well-known means for that purpose and will be delivered in large volume over the surface of the brine within the pan 14 for the purpose of accelerating evaporation from the brine and increasing 120 the rapidity of the operation taking place in the pan. The heated air may be supplied to the chamber below the hood 22 by means of a pipe 28 and blower 29.

The essential features of novelty reside in 130 the employment in a system such as de-

scribed, of means, preferably air jets, for agitating the surface of the brine in the pan 14 for the purpose of securing a variation in grain and any special grain desired, and in 5 the simultaneous introduction of heated air for evaporative purposes in large volume under the hood 22 and over the surface of the brine during the agitation of the surface of the latter. It has heretofore been proposed to use suspended "flippers" or other 10 mechanical devices for preventing the surface of the brine in the circulating pan from "scumming" over and so decreasing the rate of evaporation, the "flippers" or the like 15 having been used occasionally as the scum formed over the surface of the brine. The agitation proposed by me is not the character of agitation produced by the "flippers" of the prior art, but is special and may be 20 varied at will and is employed to control the character of grain produced, that is with respect to the fineness or coarseness of the same, and to render it possible to so operate the system that any desired grain may 25 be secured. The pipe line 25 supplying the nozzles 26 with air will preferably have an air pressure of about 80 pounds, gage. The number of nozzles 26 employed will vary with the size of the pan 14 but ordinarily 30 there should be several of said nozzles employed, all operating at the same time. With the use of the air from the pipes or nozzles 26 or other means for variably agitating the surface of the brine, said surface 35 is not only prevented from scumming, but the operator may, at will, by varying the degree of agitation, secure such proportions of fine and coarse salt as may be desired. It is of great importance that a manufacturer 40 may be enabled to secure variations in grain or kinds of salt produced since the requirements of the public demand the same. The systems heretofore employed for producing salt, and especially those analogous to the 45 general system of heating brine under pressure and releasing the pressure, hereinbefore explained, were not controllable as regards the production of grained salt of uniform, adjusted fineness to meet the various requirements of the art, and my invention has for 50 one of its purposes to remedy the objection to these previous processes and to increase the utility of the same by providing in the system suitable means for securing variations in the action taking place in the evaporator pan so that salt of the particular kind or kinds desired may be readily produced.

In addition to the agitation of the surface of the brine I preferably supply warm air 55 in large volume over such surface, as hereinbefore explained, so as to accelerate the evaporation by removing the vapor and preventing condensation as the hot vapors cool on leaving the pan. The warm air will be 60 driven into the chamber of the hood 24 by

a fan or the like 29, and this air being present with the surface of the brine in agitation, will rapidly take up moisture from the brine and carry the same through the outlet 23 of the hood, thereby hastening the operation 70 of the general system and increasing the capacity thereof. The air used for agitating the surface of the brine may also be warm air, if preferred, so as to thereby facilitate evaporation. 75

By performing the graining evaporation in an atmosphere of controlled composition, given by hood 22 in connection with sources of air 25 and 29, a control of the rate of evaporation and, thereby, of the size of salt 80 granule, is given.

I do not confine my invention to the details of the apparatus hereinbefore explained, nor in every instance to the employment of air under pressure for creating the 85 varied agitation or rippling of the surface of the brine, although the best results may be most conveniently and certainly secured when air is used for this purpose.

What I claim as my invention and desire 90 to secure by Letters-Patent is:—

1. The process of making salt from brine which comprises circulating brine through a suitable heating system and delivering it in a hot saturated condition into a main 95 evaporating or circulating pan maintained in an atmosphere of controlled composition and there allowing such brine to undergo self-evaporation, and controlling the kind of salt produced by a rippling agitation of 100 the surface of the brine in said pan to an extent governed by the size of grain desired.

2. The process of making salt from brine which comprises circulating brine through a suitable heating system and delivering it in 105 a hot saturated condition into a main evaporating or circulating pan maintained in an atmosphere of controlled composition, there allowing such brine to undergo self-evaporation, and controlling the kind of salt produced by agitation of the surface of the brine in said pan to an extent governed by 110 the size of grain desired, by fine jets of air under pressure directed against such surface.

3. The process of making salt from brine which comprises circulating brine through a suitable heating system and delivering it in a hot saturated condition into a main evaporating or circulating pan maintained in an 115 atmosphere of controlled composition, there allowing such brine to undergo self-evaporation, and controlling the kind of salt produced by agitation of the surface of the brine in said pan to an extent governed by the size of grain desired, by fine jets of air under pressure directed obliquely against such surface and creating a rippling thereof.

4. The process of making salt from brine which comprises circulating brine through a suitable heating system and delivering it in 120

5 a hot saturated condition into a main evaporating or circulating pan maintained in an atmosphere of controlled composition, there allowing such brine to undergo self-evaporation, and controlling the kind of salt produced by agitation of the surface of the brine in said pan to an extent governed by the size of grain desired, by a series of jets of air under pressure directed obliquely 10 against such surface in an inward direction from the outer portions thereof.

15 5. The process of making salt from brine which comprises circulating the brine through a suitable superheating system into a hooded main evaporating or circulating pan in which the salt is formed, said pan being provided with a vapor discharge outlet and with means for controlling the composition of the atmosphere within the hood, 20 and controlling the kind of salt produced by agitation of the surface of the brine in said pan to an extent governed by the size of grain desired, by jets of air under pressure directed against such surface.

25 6. The process of making salt from brine comprising circulating the brine through a suitable superheating system into a main evaporating or circulating pan in which the salt is formed, and controlling the kind of 30 salt produced by agitation of the surface of the brine in said pan to an extent governed by the size of grain desired, in the presence of a constant volume current of heated air delivered over said surface.

35 7. The process of making salt in varied grades from a body of hot self-evaporating brine which comprises inclosing a vapor space above the surface of such body in such manner as to permit a limited escape of 40 vapors and agitating the surface of the body of brine to an extent determined by the character of grain desired while constantly removing precipitated salt from the bottom of such body.

45 8. The process of making salt in varied grades from a body of hot self-evaporating brine which comprises inclosing a vapor space above the surface of such body in such manner as to permit a limited escape of vapors and agitating the surface of the body of brine to an extent determined by the character of grain desired by means of air under pressure directed against such surface while 50 constantly removing precipitated salt from 55 the bottom of such body.

9. The process of making salt in varied grades from a body of hot self-evaporating brine which comprises inclosing a vapor space above the surface of such body in such manner as to permit a limited escape of 60 vapors and agitating the surface of the body of brine to an extent determined by the character of grain desired by means of air under pressure directed obliquely against such surface in such manner as to create a rippling 65 thereof while constantly removing precipitated salt from the bottom of such body.

10. The process of making salt in varied 70 grades from hot self-evaporated saturated brine contained in a covered pan vented for the escape of vapor, which comprises the agitation of the surface of the brine in said pan to an extent determined by the character of grain desired by means of air under pressure directed against such surface, in the 75 presence of a constant volume of heated air delivered over said surface, with constant removal of the salt so precipitated from the bottom of the pan.

11. The process of making salt from brine 80 which comprises establishing and maintaining a body of self-evaporating saturated brine underneath a vapor chamber while permitting a limited escape of vapor, transmitting hot self-evaporating brine into such 85 body, delivering heated air to said body, controllably agitating the surface of said body and removing salt from the bottom of said body.

12. The process of making salt from 90 brine in a circulating system which comprises superheating brine under pressure, filtering the brine under pressure, releasing the pressure, delivering the released brine into an evaporating chamber as a body of 95 large surface, delivering heated air in large volume over said surface, rippling the surface of the brine to precipitate salt crystals, constantly removing such salt crystals and returning brine so treated for circulating 100 through the system anew, fresh brine being added in the circulation prior to the superheating step.

Signed at St. Clair, in the county of St. Clair and State of Michigan, this 2nd day of 105 May, 1911.
